UNITED STATES PATENT OFFICE

J. B. MERIAM, OF CLEVELAND, OHIO.

IMPROVED APPARATUS FOR EXTRACTING PARAFFINE, &c., FROM OIL.

Specification forming part of Letters Patent No. 61,946, dated February 12, 1867.

To all whom it may concern:

Be it known that I, J. B. MERIAM, of Cleveland, in the county of Cuyahoga and State of Ohio, have invented certain new and useful Improvements in an Apparatus for Extracting Paraffine, Stearine, &c., from Oils; and I do hereby declare that the following is a full and complete description of the construction and operation of the same, reference being had to the accompanying drawings making a part of this specification, in which—

Figure 1 is a side view of the press. Fig. 2 is a front view. Fig. 3 is a top view of the same. Fig. 4 is a top view of the refrigerator. Fig. 5 is a side view of the same. Fig. 6 is a bucket to be referred to.

Like letters of reference refer to like parts in the several views.

This apparatus consists of a press and refrigerator, and is constructed in the following manner:

The press consists of a strong square wooden frame, A, Figs. 1 and 2, and is placed in a pan or receiver, B, which is lined with zinc or other suitable metal. Both are then firmly secured to the floor or platform C. D is a cross-head, to which is attached the follower E by means of the link F. The ends of the cross-head slide upward and downward between the stanchions G, which serve as a guide for the movement of the head, and also to retain it in its proper position. These stanchions are framed into cross-bars H, the upper one being the shortest, and is connected to the frame A by the hinge a, Fig. 2, so that it can be lifted up for a purpose hereafter shown. J is a shaft reaching across the bottom of the press, and is connected to the cross-head D by the chain and loop K. L is a lever keyed to the end of the shaft J, and by which it is operated, as will hereafter be shown. M is a rope, one end of which is attached to the lever L, and extending from thence over the sheaves N, down to the windlass O, Fig. 2, the purpose of which is to raise the weighted lever L from a horizontal position to that shown in the drawing, and thereby operating the press, as will be hereafter described. P is a barrel or cylinder, and is constructed of any fine-grained wood; or it may be of iron—if wood, care being taken to have the grain run outward in its upward

cleavage, so that the fiber may not ruff up or splinter as the follower shall descend within it while in the process of pressing. The inside surface of this cylinder is fluted or ribbed longitudinally, as shown in Fig. 2, a section of which is broken away in order to show the flutes or ribs b.

The follower E, above referred to, is so fitted to the inside of the cylinder that the dependent arms c fit between the ribs closely, but not so closely as to prevent it from sliding freely up and down within. The arms are so made to fit close to the bottom of the flutes, so that when the follower is moving the face of the ribs shall not touch the disk, to which the arms are connected, and which disk forms the head of the follower; hence, by this means, the face of the ribs is prevented from being chafed by the follower rubbing against it while in operation.

Having thus described the construction and arrangement of the press, I will now describe the refrigerator, which consists of a strong wooden tank, Q, Fig. 5, the height of which being some four or five feet, and the length according to the number and capacity of the presses used. This tank is provided with an inner or false bottom, R, Fig. 4, and is perforated with holes. Between this inner and the outer bottom is a space, to which reference will hereafter be made. Within the tank is arranged a number of galvanized-iron cases or cylinders, S, which stand upon the perforated bottom, and are of about the same height of the tank. A few only are shown in the drawing. The whole tank, however, is supposed to be filled with the cases in the same order.

Any number of tanks may be constructed and arranged in the same way, according to the capacity or number of presses run in the works.

The cases, when properly arranged, are then filled with oil by means of the conducting-pipe T, leading directly from the oil-vats above, and, when full, the interstices between them are filled up with a freezing-mixture of pounded ice and salt. By this means the temperature of the oil is quickly reduced to a degree ranging from 10° to 15° Fahrenheit. At this temperature it is quite thick or solid. It is then taken from the cases and put into the

press, as follows: A metallic bucket, U, Fig. 5, is made to fit in the cases, the bottom of which is provided with a valve, V, opening inward, the capacity of the bucket being one-third the contents of a case. The thick oil is first cut or broken up by a cross-bladed cutter provided for that purpose, and when thus loosened up the bucket is forced down into the case, the oil filling the bucket through the valve above referred to, and when full it is then withdrawn, and the contents emptied into a strong canvas bag, which is then securely tied and placed in the cylinder P. First, however, the cylinder is lined with a thick canvas, and the bag placed within, so that it does not touch the sides directly. The contents of one case fill three bags. This constitutes the first layer of bags, and then another layer of bags, &c., three layers filling the cylinder. The lining of the cylinder referred to is then drawn over the top and the follower drawn down upon it. The power of the press is then applied by the lever L, which, on being brought downward by the weight W, causes the chain to draw down the cross-head, forcing thereby the follower down upon the bags, the degree of pressure being as the distance of the weight from the fulcrum.

It will be seen that the dependent arms of the follower pass down between the sides of the cylinder and the bags, and between the ribs; hence the contact of the bags with the cylinder is only on the face of the ribs, and that the follower does not touch the ribs at any point on their faces. Therefore there is no chafing or rubbing of them, so as to cause splinters to penetrate or tear the bags, and thereby allow the oil to escape. By this means the inside of the cylinder is at all times kept smooth, and the parts of which in contact with the bags free from the follower, by the arms pressing against the bottom of the flutes, which constitute the sides of the cylinder.

In order to lessen the friction of the cross-head, caused by its lateral pressure exerted against the guides or stanchions G while in operation, friction-rollers are so placed on the cross-head as to roll against the inside of the stanchions. These rollers are indicated by the dotted line c', Fig. 2.

When the lever L has dropped to a horizontal position by the expressing of the oil, it is again raised up for a still further pressing by the rope and windlass above described. This winding up of the lever is repeated until all the oil has been extracted, the oil as it is pressed out from the cylinder through apertures made in the side of the bottom into the pan B, by means of which it is conducted into barrels or otherwise disposed of. When the process of pressing has been completed, the follower is then drawn from the cylinder by the rope d, and the stanchions lifted up out of the way by the rope e. The cylinder is then turned over, and the bags removed and again filled by others, as before described, and the

pressing power applied, as in the former case. As fast as the cases are emptied of the chilled oil they are again filled and covered, and the interstices between which at all times kept full of the freezing-mixture. The ice as it melts flows off through the perforated bottom referred to, and out of the spout f, Fig. 4, into the sewer. By this means the mixture is kept free from water, and, in consequence, much cooler.

It is a well-known fact that winter-pressed oils are much more limpid, and better for lubricating and illuminating purposes, than oils pressed in the summer, for the reasons that oils pressed in the winter and at low temperature contain less paraffine and stearine than oils pressed at high temperatures. It is owing to the presence of this paraffine and stearine that oils chill any thicker in cold weather; hence they will not flow from the cans, thereby rendering them useless for the purpose of lubrication; but by pressing them under a low temperature, which can be easily done in the winter season, nearly if not quite all the paraffine and stearine is left in the press, and the oil thus obtained will stand a degree of cold without thickening that will render them fit for railway machinery or machinery exposed to the cold weather. As above remarked, when oils are pressed in a warm temperature, the paraffine and stearine are in a fluid state, and flow out from the press along with the oil; but when pressed under low temperature, the paraffine and stearine are thick or solid, and remain in the press while the oil flows off. In order to accomplish the latter result in warm weather, as in summer, I subject the crude oil to the influence of the freezing-mixture in the manner above described. Thereby we obtain an oil equal in character to winter-pressed, and which will retain its fluid state in a temperature of ten degrees or less. By this process of chilling the crude oil before pressing the same, and by having the cylinder tight, whereby the bags are excluded from the air, and by this kept colder for a much longer space of time than could be by the old press, also by the greater facility of getting the oil into the press, and by increasing the power of the same by reducing the friction by the introduction of the friction-rollers, I am enabled to manufacture winter-strained oil all the year round.

What I claim as my improvement, and desire to secure by Letters Patent, is—

1. The stanchions G, pulleys d, N, and O, as arranged in combination with the frames A and pan B, for the purpose and in the manner set forth.

2. The cross-head D, friction-rollers c', in combination with the stanchions G, as arranged and operated by the links K and levers L, for the purpose and in the manner specified.

3. The cylinder P as constructed with ribs or corrugations b on the inner surface, as and for the purpose specified.

4. The follower E, with the dependent arms e, in combination with the cylinder P, for the purpose and in the manner as substantially described.

5. The arrangement of the cases S, bucket U, pipe T, in combination with the tank Q, provided with the perforated bottom R, as and for the purpose set forth.

6. The cases S, buckets U, in combination with the tank Q and freezing-mixture, for the purpose and in the manner as described.

J. B. MERIAM.
